UNITED STATES PATENT OFFICE

2,453,948

MOP GRIPPING UNIT FOR MOP SHAKING
MACHINES

Clarence Turnepseed, Springfield, Ohio

Application April 5, 1946, Serial No. 660,015

5 Claims. (Cl. 15—94)

1

The object of the present invention is to provide a new and simplified mechanism for securely gripping and holding mop handles during the operation of imparting a vigorous shaking movement to the mop for the purpose of cleaning the same.

The invention is an improvement in machines for cleaning dust mops and dust cloths of the character of that shown in my co-pending application, Serial No. 568,304, filed on December 15, 1944 which issued January 6, 1948 as Patent Number 2,434,022. The basic idea, common to both the aforesaid application and the present application, is that a rapid oscillatory movement is imparted to a member that is held at an inclination with respect to the vertical (preferably at an angle of about 30°) said member being provided with gripping means for holding the handle of the mop substantially vertical. The net result is to impart a vigorous vertical shaking movement to the mop, both up and down and back and forth.

The invention will be best understood by reference to the accompanying drawing, wherein:

Figure 1 is a plan view of the holder constituting the essential feature of the invention;

Figure 2 is a fragmentary sectional view of a portion of a mop cleaning machine of the character shown in my aforesaid application;

Figure 3 is a detail sectional view on line 3—3 of Figure 1; and

Figure 4 is a sectional view on line 4—4 of Figure 1.

In the drawings, numeral 5 designates the casing of a mop cleaning machine which comprises a transverse support 6, a central portion 7 of which is inclined or disposed at an angle of substantially 30°. This portion 7 has tapped into it a shouldered screw 8. This screw is preferably provided with a freely rotatable bushing 9 and this bushing and screw provide a pivotal support for a tong or plier-like structure, consisting of two jaws, 10 and 11. The jaw 11 in addition to its main structure carries an apron or web 12 which extends laterally and underlies the jaw 10. This apron carries an ear 13 in which an unthreaded portion of a screw 14 is mounted to turn. This screw is held against endwise movement with respect to the ear by washers 15 and pins 16 or equivalent device. The outer end of the screw is shaped to constitute a crank that is provided with a handle 18. The threaded portion of the screw engages a threaded block 19. Ears 20 of this block are connected by pivots 21 with the inner end of links 22 and 23. The outer ends

of these links are pivotally connected to the ears 24 and 25 formed at the rear ends of the jaws 10 and 11, respectively.

It will be readily understood that when the screw 14 is turned to bring the links 22 and 23 into alignment with each other, the forward ends of the jaws 10 and 11 will be forced together under an extremely powerful leverage, such leverage being the combined action of the screw 14 and the toggle action of the links 22 and 23, and thus the forward ends of the jaws will be caused to very forcibly grip the handle of a mop, said handle being indicated at 26. The webs 10a and 11a representing the body portions proper of the jaws 10 and 11 are indicated in Figure 4 and since these jaws are carried by a pivot that is inclined at an angle of 30° with respect to the vertical it follows that the tong-like structure also, as a whole, lies at an angle of approximately 30°. However, those portions of the jaws which actually contact and grip the handle 26 of the mop consist of ribs or flanges 10b, 11b and these flanges are vertical flanges (See Figure 4). Rapid oscillating motion about the pivot constituted by the bolt 8 may be imparted to the tong-like structure by a reciprocatory connecting rod 27, this rod corresponding to the reciprocatory connecting rod 18 of my aforesaid application. The means for imparting reciprocation to the rod 27 constitutes no part of the present invention. It is clear that any simple motor-driven crank mechanism will efficiently serve this purpose. I preferably make the pivotal connection between the rod 27 and the jaw 11, which it engages, a loose one, the purpose of this being to provide an additional jerk to the structure for the purpose of aiding in shaking the dirt loose from the mop.

I also contemplate supporting a transverse arm 28 from the web 12, said arm carrying a conventional spring clip of the spring clothes pin type, indicated at 29. This clip serves the function of clamping a dust cloth to the arm so that the dust cloth may be shaken in the same way that the mop is shaken.

45 It is to be understood that the invention is not limited to the precise construction set forth but that it includes within its purview, whatever changes fairly come within either the terms or the spirit of the appended claims.

50 Having described my invention, what I claim is:

1. A device of the character described comprising a tong-like structure, means for mounting said tong-like structure for bodily oscillation in a plane inclined with respect to the vertical,

means carried by the tong-like structure shaped and dimensioned to grip a mop handle and hold it in a substantially vertical position at an intermediate position of the tong like structure along its path of oscillation and manually operable means for forcing the tong-like structure into tight gripping engagement with said handle.

2. A device of the character described, comprising a support, including a pivot inclined with respect to the vertical, a tong-like structure comprising a pair of jaws pivotally mounted upon said pivot, mop handle gripping portions carried by said jaws, and means for imparting oscillation to the tong-like structure as a whole, said gripping portions having gripping surfaces disposed at such an angle as to hold the mop handles substantially vertical at an intermediate point in the oscillation of the tong like structure.

3. A device of the character described, comprising a support, including a pivot inclined with respect to the vertical, a tong-like structure comprising a pair of jaws pivotally mounted upon said pivot and movable in a plane perpendicular to the axis of said pivot, mop handle gripping portions carried by said jaws, the gripping surfaces of which lie substantially vertical at an intermediate position of the tong-like structure along its path of oscillation, means for imparting oscillation to the tong-like structure as a whole about said inclined pivot, and means for imparting gripping action to the tong-like structure comprising a manually operable screw and means engaging said screw with the tong-like structure which permits rotation of the screw but prevents endwise movement of the screw with respect to the tong-like structure and a toggle mechanism engaged with the screw and with the jaws of the tong-like structure for imparting gripping action to said jaws under the combined action of the screw and the toggle mechanism, said toggle mechanism and screw swinging bodily with the tong-like structure in its oscillation.

4. In a device of the character described, the combination with a support of a pivot carried by said support and inclined with respect to the vertical, a tong-like structure mounted for oscillation about said pivot in a plane perpendicular to the axis of said pivot and comprising a pair of jaws having rear ends and forward ends, a

threaded block, toggle links connecting said block with the rear ends of said jaws, a cranked screw having threaded engagement with said block, means mounted upon one of said jaws with which the inner end of said screw is engaged and which holds said screw against endwise movement with respect to said jaw while permitting said screw to turn, and flanges carried by the forward ends of said jaws shaped to engage the handle of the mop under the combined action of the screw and toggle links, which flanges lie in substantially vertical planes at an intermediate position of the tong-like structure along its path of oscillation.

5. The combination with a support of a pivot carried by said support and inclined at approximately a 30° angle with respect to the vertical, a tong-like structure comprising a pair of confronting jaws mounted upon said pivot for movement toward, and from, each other, one of said jaws embodying a lateral web which underlies the other of said jaws, an ear carried by said web, a screw mounted to turn in said ear, said web lying immediately over said support, means for thrusting the rear ends of the jaws forcibly apart to thereby bring their forward ends forcibly together, means for imparting oscillation to the tong like structure about said pivot and flanges outstanding from the forward end of the jaws said flanges being shaped and dimensioned to engage a mop handle and lying in substantially vertical positions at an intermediate position of the tong like structure along its path of oscillation.
